[57] CLAIM

The ornamental design for a transceiver housing, as shown and described.

DESCRIPTION

FIG. 1 is a right, front, bottom view of a transceiver housing, showing our new design;

FIG. 2 is a right side elevation view thereof;

FIG. 3 is a front elevation view thereof;

FIG. 4 is a bottom elevation view thereof;

FIG. 5 is a left side elevation view thereof;

FIG. 6 is a rear elevation view thereof; and

FIG. 7 is a top elevation view thereof;

FIG. 8 is a right, front, bottom view of that shown in FIG.

1 without the broken line description;

FIG. 9 is a left side elevational view thereof;

FIG. 10 is a rear elevational view thereof; and,

FIG. 11 is a top elevational view thereof.

The broken lines shown in FIGS. 1-7 are for illustrative purposes only and form no part of the claimed design.
